UNITED STATES PATENT OFFICE.

JOHN ROSS, OF SAN FRANCISCO, CALIFORNIA.

BUCKET ELEVATOR.

No. 833,417.

Specification of Letters Patent.

Patented Oct. 16, 1906.

Application filed February 28, 1906. Serial No. 303,428.

To all whom it may concern:

Be it known that I, JOHN ROSS, a citizen of the United States, residing at San Francisco, in the county of San Francisco and State of California, have invented new and useful Improvements in Bucket Elevators, of which the following is a specification.

This invention relates to an improved construction of turn-table and hoisting-gear for elevators such as are used for unloading vessels and for other purposes where material of various kinds is to be conveyed from one level to another.

The invention is applicable more particularly to elevator mechanism for discharging broken rock or stone from a scow onto the wharf, where the material requires to be raised to a higher level; and it has for its object chiefly to provide improved means for adjusting or changing the position of the elevator at will to work at different angles and for operating the elevator under every condition or degree of adjustment without disconnecting the elevator from the power or throwing it out of operation.

To these and other ends my said invention comprises certain novel construction and combination of turn-table and hoisting-gear, as hereinafter described, and pointed out in the claims at the end of this specification, reference being had therein to the accompanying drawings.

Figure 1 is an elevation, partly in section, of the part of an endless-chain and bucket elevator to which my improvements pertain, the ladder or frame, the turn-table, and the operating-gear being shown in transverse section. Fig. 2 is a side view of the parts represented in Fig. 1. Fig. 3 is a plan or top view of the stationary bed-plate beneath the turn-table and the foundation-timbers. Fig. 4 is a front elevation of the bed-plate, and Fig. 5 is a side view of Fig. 4. Fig. 6 is a top view of the turn-table, and Fig. 7 is a front elevation of the same. Fig. 8 is a side view of one of the trunnion-boxes on the ends of the ladder. Fig. 9 is a face view of one of the bearing-boxes for a trunnion. Fig. 10 is a side view of Fig. 9.

The stationary bed-plate has a flat top *a*, formed with a circular bearing-surface 2, with which engages an annular bearing-surface on the bottom plate *b* of the turn-table. The

stationary bed is secured to bed-timbers *d* by bolts 3. A tubular center post 4, surrounding a central opening in the top plate *a*, forms a long stiff bearing for the center post 8 of the turn-table *b*. The bed-plate *a* also supports bearings 9 for the inner ends of two rotatable shafts 10 12, the outer ends of the shafts being supported by boxes 13 14, also supported by the said bed-plate. One of these last-mentioned shafts is coupled to or connected in any suitable manner with the engine-shaft from which power is supplied to operate the elevator, such as through a clutch or by a belt and pulleys, whereas the other shaft 12, running idly, is arranged to carry an idle pinion 16.

From the shaft 10 the power is applied to the upright shaft 17, extending through the center post of the turn-table, by means of a bevel-gear 18, keyed on the lower end of the shaft 17, and a beveled gear 21, keyed on the upper end of the shaft. A beveled pinion 22, keyed on the shaft 20, connects the latter shaft with the upright shaft 17.

Like the pinion 16, that is in mesh with the lower gear 18, a beveled pinion 23 is placed on the shaft 20 opposite to the driving-pinion 22, and being loose on the shaft 20 it is arranged to counteract the angular strain of the gears 18 21 on its shaft as the power is transmitted through the gear 18 to the pinion 22 on the driven shaft.

The tubular post 8 on the under side of the turn-table is lined with Babbitt metal, and an antifriction-bearing 25 is interposed between the top face of the turn-table at the center bearing 24 and the lower face of the beveled gear 21. The opposing faces of the bed-plate and the turn-table are faced, as seen in Figs. 1, 3, and 4, to give a firm bearing around the center post and also around the outer margin of the bed-plate, the intermediate part of the surface on both bed-plate and turn-table being recessed to reduce the extent of frictional contact.

The standing sides 30 and ends 31 of the turn-table are integral with the bottom plate. On the standing sides are hubs 29, that form bearings for the horizontal shaft 20 and also trunnions for the lower ends of the elevator-frame.

The turn-table *b*, the center post 8, standing sides 30, and hubs 29 and the end pieces

31 are formed in one piece. The standing sides have slanting top edges, as seen at 32, Figs. 2 and 8, to which are fitted top plates 33 to cover and protect the gearing from dust 5 and particles of rock that are liable to drop from the buckets.

The surface of the bed-plate and the turn-table mutually cover and protect each other and the bed-plate in turn protects the pins 10 and driving-gear that are situated beneath the bed-plate, as the boxes and bearings that carry the driving-shafts are located within the sides of the bed-plate.

Boxes 34 on the lower ends of the elevator frame *g* take the trunnion 29, on which the frame is movable axially. The boxes have caps or end pieces 35 of semicircular shape concentric with the axis of the trunnions and each fitted to a cradle-block 38 on the outer 15 faces of the standing side 30 below the trunnion. These cradle-blocks extend upward behind the boxes 34 and may be faced with Babbitt metal to reduce the friction. Placed in this position, they relieve the trunnions of 20 the weight and thrust of the elevator-frame when under a full load.

The construction of the parts carried by the turn-table and those mounted on the bed-plate is such that the turn-table can be 25 moved around the upright shaft 17 as an axis, and the direction as well as the angle of the elevator-frame can be changed as conditions require without disconnecting the power or affecting the operation of the hoisting mechanism on the elevator-frame. The hoisting power is applied to the chain of buckets by 30 sprocket-wheels 36 37 and a chain belt 38' on both sides of the frame connecting both ends of the shaft 20 with a bucket-operating shaft 35 40 on the frame. The bucket *k* of the form usually employed in these elevators is fastened to four endless cables 41 42 43 44, of 45 which the two inner ones 42 44 transmit the power from the bottom shaft 20 to the top shaft 45, carried in bearings 46 on the upper end of the elevator-frame, and the outer ones 41 43 support the buckets and connect them together in an endless chain or row. The cross-bars 48 are fastened to the cables 41 43 50 by straps passing around the cable and riveted to the bars and pouring Babbitt metal between the strap and the strands of the cable. This forms a simple and effective means of securing the bars to the cables. The buckets 55 are fastened to the bars 48 by bolts or rivets. Removable caps should be provided on the boxes that carry the shafts 10 12 under the bed-plate. As thus constructed and arranged this mechanism is especially adapted 60 for handling and adjusting the elevator such as is employed for conveying rock and other heavy material from a lower to a higher level.

The turn-table is constructed with a view

to relieve the center-post of the weight and strain of the load to the best advantage, and 65 the arrangement of the gears and pinions is such that the turn-table is readily rotatable even under a heavy load.

By moving the elevator-frame on its trunnions the degree of inclination is changed, and 70 by rotating the turn-table on its axis 17 the frame can be set in any desired direction around the circle.

The elevator-frame is supported from the upper end in the usual manner by cables and 75 tackle, the arrangement and application of which are too well known to require a detailed description.

All parts of the elevator not necessary to a clear understanding of the invention are 80 omitted from the drawings and the description.

What I claim as my invention, and desire to secure by Letters Patent, is—

1. In an elevator mechanism the stationary bed-plate having a tubular center post, a circular bearing-surface concentric with the center post, and bearings for oppositely-set shafts; and a turn-table comprising a tubular post rotatable in the center post of 85 the bed-plate, a top plate on the center post, standing sides thereon, hubs on the standing sides and cradle-blocks on the outer faces of the standing side under the hubs, in combination with an elevator-frame having boxes 90 on the lower ends provided with a semicircular cap-piece.

2. In an elevator of the character described, a stationary bed-plate having a tubular center post, a rotatable top plate having a 95 tubular post fitted to turn in the center post of the bed-plate, standing sides on the top plate, a horizontal shaft rotatably mounted in the side plates, a horizontal driving-shaft mounted beneath the bed-plate, and gearing 100 connecting the driving-shaft and the shaft on the top plate, comprising an upright shaft extending through the center post, a beveled gear fast on the end of the upright shaft above the top plate, a similar gear on the end 105 of said shaft beneath the bed-plate, and beveled pinions on the horizontal shafts, and means connecting the horizontal shaft on the top plate with the parts to be operated.

3. In an elevator of the character herein 115 described, the stationary bed-plate having a tubular center post, a top plate rotatable on the bed-plate and having a center post rotatably mounted in the post of the bed-plate, an upright shaft extending through the center 120 post of the top plate, bearings for a horizontal shaft on the top plate, said bearings also forming trunnions for the elevator-frame, a shaft rotatable in said bearings, a beveled gear on the upper end of the upright shaft, a pinion fast 125 on the horizontal shaft above the top plate

and connecting that shaft with the said beveled gear, a horizontal driving-shaft below the bed-plate and a beveled gear and pinion connecting together said horizontal shaft and 5 upright shaft and idle pinions loose on said horizontal shafts for counterbalancing the driving pinions.

In testimony whereof I have hereunto set my name to this specification in the presence of two subscribing witnesses.

JOHN ROSS.
